US0D1066626S

(12) **United States Design Patent** (10) Patent No.: **US D1,066,626 S**
(45) Date of Patent: ** Mar. 11, 2025

(54) **HOUSING SHROUD FOR AN AIR CONDITIONER**

- (71) Applicant: **Dometic Sweden AB**, Solna (SE)
(72) Inventors: **Rickard Hederstierna**, Hägersten (SE); **Samuele Meda**, Chichester (GB); **Todd Jason Jurek**, Elkhart, IN (US)
(73) Assignee: **Dometic Sweden AB**, Solna (SE)
(**) Term: **15 Years**
(21) Appl. No.: **29/936,908**
(22) Filed: **Apr. 11, 2024**

Related U.S. Application Data

- (63) Continuation of application No. 29/798,939, filed on Jul. 12, 2021, now Pat. No. Des. 1,027,143.

CLAIM

The ornamental design for a housing shroud for an air conditioner as shown and described.

DESCRIPTION

FIG. 1 is a perspective view of a design for a housing shroud for an air conditioner;

FIG. 2 is a front view of the design of FIG. 1;

FIG. 3 is a first side view of the design of FIG. 1;

FIG. 4 is a second side view of the design of FIG. 1;

FIG. 5 is a top view of the design of FIG. 1; and,

FIG. 6 is a bottom view of the design of FIG. 1.

The broken lines shown in the drawings are included for the purpose of illustrating the unclaimed boundary or unclaimed portions of the housing shroud for an air conditioner. The broken lines form no part of the claimed design.

1 Claim, 6 Drawing Sheets
